UNITED STATES PATENT OFFICE

PAUL K. BONEBRAKE, OF CHICAGO, ILLINOIS, ASSIGNOR TO MONTGOMERY WARD & CO., INCORPORATED, OF CHICAGO, ILLINOIS, A CORPORATION OF ILLINOIS

DESIGN FOR A WATCHCASE

Application filed October 7, 1929. Serial No. 32,966. Term of patent 7 years.

To all whom it may concern:

Be it known that I, PAUL K. BONEBRAKE, a citizen of the United States, residing at Chicago, in the county of Cook and State of Illinois, have invented a new, original, and ornamental Design for a Watchcase of which the following is a specification, reference being had to the accompanying drawing, forming a part hereof.

In the drawing, Figure 1 is a plan view of the back of a watch showing my new design; and Figure 2 is an edge elevation of the same.

I claim:

The ornamental design for a watch case, substantially as shown.

PAUL K. BONEBRAKE.
